UNITED STATES PATENT OFFICE.

JOSEPH I. DUNTLEY, OF LYNN, MASSACHUSETTS.

WINDOW-SCREEN.

1,159,194.

Specification of Letters Patent.

Patented Nov. 2, 1915.

Application filed December 8, 1914. Serial No. 376,075.

To all whom it may concern:

Be it known that I, JOSEPH I. DUNTLEY, a citizen of the United States, residing at Lynn, in the county of Essex and State of Massachusetts, have invented certain new and useful Improvements in Window-Screens, of which the following is a specification.

My invention relates to window screens and it has for its object to provide an improved article of this class and also to provide an attachment for ordinary window screens which, when applied to a screen, makes it possible to operate an awning located upon the outside of the building without disturbing the screen.

The invention consists of a window screen, and of an attachment for a window screen, embodying the novel features of construction and operation set forth in the following description and particularly pointed out and defined in the claims at the close thereof.

In the accompanying drawings: Figure 1 is an elevation of the inner side of a window screen embodying one form of my invention. Fig. 2 is a sectional view of a portion of a building showing my improved screen applied thereto. Fig. 3 is an enlarged detail of a portion of a window screen showing the attachment, forming part of my invention, applied thereto. Fig. 4 is an elevation of the opposite side of the attachment. Fig. 5 is an end view of the attachment. Fig. 6 is a sectional detail.

The window screen shown in Figs. 1 and 2 comprises a rectangular frame A provided at each side thereof with metal eyes a by means of which the screen is fastened in the position in the window that it is to occupy.

About midway of the height of the screen is a cross bar a¹ which, together with the lower portion of the frame A, provides a rectangular opening a² at the lower end of the frame work within which is removably secured a rectangular supplemental frame A¹ to which is permanently secured in the usual fashion, a piece of wire netting a³.

In order to secure the supplemental screen A¹ within the main frame A the latter is provided upon its outer side with an inwardly projecting flange a⁴ which may be made from molding secured to the outer side of the frame A, and the supplemental screen A¹ occupies a position between this flange a⁴ and three fasteners a⁵ each, as shown in Fig.

6, consisting of a right angled piece of wire having one branch thereof threaded and screwed into the main frame of the screen so that the branch of said fastener which is upon the exterior of the frame can be swung or rotated into or out of operative position. Within the opening a² of main frame A above cross bar a¹, and fitting snugly in one of the upper corners thereof, is secured, as by means of screws a⁶, a panel B which with the parts carried thereby constitutes my new attachment referred to above. This panel may be of wood or the like and is preferably of the same thickness as the frame A, being formed with a vertical slot a⁸ and with a hole a⁹ therethrough. Within the slot a⁸ is fastened, by means of screws a¹⁰, the supporting frame of a pulley a¹¹ and as shown in Fig. 2 one of the two usual operating cords extends from the awning frame C upwardly through the slot a⁸ and over the pulley a¹¹ with its free end upon the inner side of the screen. This cord is shown at c. Upon the inner side of panel B and immediately below the hole a⁹ is mounted a pulley d¹³ arranged so that its axis is horizontal. Secured to the outer side of the panel B at one side of the hole a⁹ is a similar pulley a¹⁴ with its axis vertically disposed. The other operating cord of the awning—said cord being shown at c¹—extends from the awning frame around a pulley a¹² secured to the outer side of the screen within the upper corner thereof opposite the corner where the panel B is located, and thence around pulley a¹⁴ through opening a⁹ and over pulley d¹³, the free end of said cord hanging down upon the inner side of the screen within the building and alongside of the cord c.

A piece of wire netting a¹⁵ having one corner thereof cut away so as to leave the panel B practically uncovered is permanently fastened at its margin to the main frame A, panel B and cross bar a¹ over the opening that is within the main frame A above said cross bar.

I consider the attachment B with its peculiar equipment of pulleys an important feature of my invention because it may, with very little labor and expense, be readily applied to an ordinary screen already constructed and in use, and when so applied makes it possible for the awning upon the outside of the window to be raised and lowered by an operator upon the inside of the

building without opening or disturbing the screen.

I provide the screen shown in Figs. 1 and 2 with the removably supplemental screen 5 A¹ so that the screen may in part be removed during the seasons when a screen is not required, the main frame A¹ with the parts carried thereby being left permanently in position.

10 When my new attachment constructed as above described is applied to a screen and secured to the latter by screws or the like which fasten the top bar and one of the side bars to said attachment the latter acts to reinforce, stiffen and strengthen the frame of the screen. This is a very desirable feature because the frames of window screens are usually made very light and frail and the incorporation of the attachment in such 20 a screen not only lengthens the life of the latter by increasing the strength and rigidity of its frame but the stiffening and strengthening functions of the panel B adapts the frame to bear the additional strain imposed 25 upon it by the awning whether it be the frame of the screen shown in Figs. 1 and 2 or the frame of an ordinary screen to which the panel B with its equipment of pulleys is applied.

30 What I claim is:

1. A window screen comprising a rectangular frame adapted to be secured in position at a window; wire netting or the like secured to said frame; a panel fitted 35 and secured within one of the upper corners of the frame, said panel being made with two cord openings therethrough; a pulley secured to said panel adjacent one of said openings for guiding one of the operating cords of an awning through said opening; two pulleys secured to said panel adjacent the other cord opening, one of said pulleys being upon the inner side of the panel at the lower side of said opening and arranged 45 with its axis horizontal and the other of

said pulleys being upon the outer side of said panel at one side of said opening and having its axis disposed vertically, and a pulley on the outside of said frame secured to the latter near the other upper corner 50 thereof.

2. The above described attachment for window screens comprising a panel adapted to fit within one of the upper corners of the frame of an ordinary screen and to be secured to said frame, said panel being made with two cord openings therethrough, a pulley secured to said panel adjacent one of said openings for guiding one of the operating cords of an awning through said opening, and two pulleys secured to said panel adjacent the other cord opening, one of said pulleys being upon the inner side of the panel at the lower side of said opening and arranged with its axis horizontal and the other of said pulleys being upon the outer side of said panel at one side of said opening and having its axis disposed vertically. 55 60 65

3. A window screen comprising a main rectangular frame having a cross bar near 70 its middle; means for attaching said frame to its support; a supplemental frame removably mounted within the main frame below said cross bar; means separably securing said supplemental frame within said main 75 frame; wire netting or the like secured to said supplemental frame; wire netting or the like secured to the main frame and cross bar above the latter; a panel secured within the main frame near the upper end of the latter and made with cord openings, and 80 pulleys secured to said panel adjacent said openings for guiding the operating cords of an awning through said openings.

In testimony whereof I have affixed my 85 signature, in presence of two witnesses.

JOSEPH I. DUNTLEY.
